METHOD OF MAKING TAMPONS

Joseph R. Crockford, New York, N. Y., assignor
to Harry Radzinsky and Sidney W. Dean, Jr.,
both of New York, N. Y.

Application December 14, 1945, Serial No. 634,952

8 Claims. (Cl. 18—55)

1

This invention relates to tampons and more particularly to the type employed during the menstrual period. The primary object of the invention is to provide an improved method and apparatus for manufacturing the same.

The invention especially relates to a method for producing a tampon composed in whole or in part of cellulose or viscose sponge materials, or of other materials of similar characteristics, a tampon of this character being shown in my Patent No. 2,254,272, dated September 2, 1941. An object of the present invention is to provide a simplified method, by which a tampon of such material or of other material, can be rapidly made in quantity and at a minimum of manufacturing cost.

Still another object of the invention is to provide an improved assembling method whereby tampons can be speedily and effectively inserted in applicators of the telescopic type, namely, those in which a plunger slidably fits within a tube in which the tampon is contained.

These and other objects are attained by the invention, a more particular description of which will hereinafter appear and be set forth in the claims appended hereto.

In the accompanying drawings, Fig. 1 shows a strip of cellulose or viscose sponge or other material of similar characteristics, indicating how the tampon bodies are cut therefrom;

Fig. 2 is a face view of one of the tampon bodies with the withdrawal string attached to the same;

Fig. 3 is a sectional view on the line 3—3 of Fig. 2;

Fig. 4 is a perspective view showing a tampon body engaged by a forked holder constituting a part of the tampon-compressing means;

Fig. 5 shows a tampon body held by the rotating forked holder and about to be inserted into the compressing tube;

Fig. 6 shows how the tampon body is compressed within the compressing tube;

Fig. 7 is a perspective view of the compressed tampon;

Fig. 8 is a side view, with parts in section, of the means for inserting the tampon into its applicator;

Fig. 9 is a sectional view on the line 9—9 of Fig. 8, looking in the direction of the arrows;

Fig. 10 is a vertical sectional view through the means for inserting the tampon in an applicator;

Fig. 11 is an enlarged side view of the tampon in its applicator;

Fig. 12 is a face view of a modified form of tampon body, and

2

Fig. 13 shows the tampon body of Fig. 12 transversely folded and having the withdrawal string looped through it.

The tampon is preferably, but not necessarily, a single-piece section of cellulose or viscose sponge material or a material of generally similar characteristics, and for simplicity and economy in manufacture, the body of the tampon may be stamped out or cut from sheet sponge, preferably in strip form, and preferably, but not necessarily, the width of a tampon. Such a strip is disclosed at 1 in Fig. 1 and by being severed on the diagonal lines 2 extending transversely of the strip 1, the wedge-shaped tampon bodies 3 may be very rapidly and economically cut from the strip without material waste. When cut from the strip, each tampon body consists of a relatively flat but fairly thick sheet 3 which is wider at one end than at the other, the wider end 5 being the top or "head" of the tampon, the narrower end 4 being the bottom or rear end. In other words, the tampon body is preferably of wedge or so-called "keystone" shape. I have found it desirable to form the bodies of the tampons into this shape because such a shape not only tends to prevent accidental dislodgement of the tampon from the vaginal cavity but it also presents the greater mass of absorbent material where it is most needed, namely, at the entrance to the uterus.

To a tampon body of the shape described is secured a withdrawal string in any suitable manner, an example of a suitable means of attachment being by the extension of a line of stitching 6 down the center of the tampon body as clearly shown in Fig. 2, the stitching being continued beyond the narrower end 4 of the tampon for a sufficient length to provide a flowing or free end 7 used as a pull string by which the tampon is withdrawn from the vaginal orifice.

The tampon body, in either the form shown in Fig. 2, or of other suitable shape, is next engaged by a suitable rotating holder, such as the member 8, which is bifurcated or forked to produce 45 the spaced prongs 9 which frictionally or otherwise engage or grip the tampon body between them and firmly hold it along its center line, while the holder 8 is then rotated about its longitudinal axis. While the tampon body 3 is so held and is being rotated while in the grip of the holder 8, it is inserted within a compressing tube, which is provided at its mouth or entrance end with a conical portion 10 facilitating the insertion of the tampon into it. As the tampon is 50 moved downwardly while being rotated, it passes 55

3

from the conical portion 10 into the reduced-diameter portion 11 of the compressing tube, the internal diameter of the latter being that to which the tampon is to be compressed. It will be obvious that when the tampon is rotated within the portion 11 of the compressing tube, the tampon will be rolled up and compressed into a cylindrical body conforming in diameter to the interior of the tubular portion 11 of the compressing tube, the resultant tampon being shown in Fig. 7.

While the tampon body so compressed will be of uniformly cylindrical shape due to its conformation to the interior of the tube 11, certain portions of the tampon body will have been compressed more than others, due to the use of more material in the first-mentioned parts. That is to say, the wider end portion 5 of the tampon having more material in it than the narrower end 4, it is obvious that the end 5 will be required to be more compressed than the narrower end to result in the formation of a cylindrical body of uniform diameter. On the other hand, the wider end of the tampon, after being inserted in the vagina and subjected to the menstrual flow, will spread to its normal width and will present the greatest area at the location where it is most required, namely, at the entrance to the uterus. Moreover, the wedge shape of the tampon body will tend to hold it securely within the vagina and prevent its accidental dislodgement therefrom.

The compressed or rolled-up tampon shown in Fig. 7 is ready for use and can be inserted in the vaginal orifice by thrusting it in position with the fingers, or it may be inserted in an applicator which includes a plunger by means of which the tampon is expelled from its applicator and into the vagina. An applicator of this character usually consists of a larger-diameter sleeve or tube 22 of cardboard or similar material and containing the tampon, and a smaller-diameter push-tube or plunger 23, also of cardboard, said plunger being arranged telescopically in relation to the tube 22, the smaller tube constituting the means by which the tampon is expelled from the tube 22.

In Figs. 8, 9 and 10 is shown the means by which the tampons can be expeditiously inserted in applicators of the character just described. Said means includes a supporting base, table, or other flat support 18 from which a sleeve 14 arises, the sleeve having a base flange 17 by means of which it is fastened to the top of the table 18. Located concentrically within the sleeve 14 and spaced from the inner wall surfaces thereof, is a smaller-diameter sleeve 20, the spacing of the same from the inside of the outer sleeve 14 providing an annular chamber 21 (Fig. 9) to closely accommodate one of the tubes 23 in an upright position.

The inner sleeve 20 extends through the table 18 to the under side thereof, said sleeve 20 being provided with the flange 24 by means of which it is secured to the under surface of the table and having a nipple portion 25 for attachment to a suction tube 26. Suction tube 26 extends from a suitable mechanism by means of which suction is exerted through the tube 26 to cause the withdrawal string 7 of a tampon inserted in one of the tubes 22 to be drawn down through the sleeve 20 and consequently through the plunger sleeve 23 which surrounds sleeve 20.

When the tampons are to be inserted into tubular applicators of the character described, or

4

possibly of other construction, a compressing device as shown in Fig. 10 may be employed. Such a compressing device may be similar to that shown in Figs. 5 and 6 but may be provided with a flared end 13 adapted to fit over the end of an applicator tube 22 which is placed around the upper end of the sleeve 20, and the plunger or push-tube 23 then disposed between the sleeve 20 and the outer sleeve 14. It will be noted that the sleeve 14 is provided at its top with a radial flange 16 upon which the tube 22 rests while the tampon is being inserted within the same.

In carrying out the procedure of inserting a tampon in the applicator, one of the plunger tubes 23 is first dropped in place in the annular chamber 21 located between the sleeves 14 and 20 and it comes to rest upon the top of the table 18 with a portion of it projecting above the top or flanged end 16 of the sleeve 14. The inner sleeve 20 rises above the top of the table 18 for a distance equal to the length of the upwardly projecting part of the plunger tube 23, so that said inner sleeve also projects above the top of the outer sleeve 14.

Next, a cardboard applicator tube 22 is placed about the protruding portion of the tube 23, the tube 22 having its lower end brought to rest on the flange 16 and standing upright. The compressing tube is then brought downwardly to bring its flared end 13 over the open top of the applicator tube 22, and a plunger 12, which may be the forked member 8, forces the tampon 3 out of the tube 11 and down into the applicator tube 22 to an extent permitted by the upper ends of the sleeve 20 and tube 14 or either of them if one of them extends upwardly more than the other. The parts of the device in the positions just described are shown in Fig. 10.

While the tampon is being inserted into the applicator, or perhaps at the ends of the inserting stroke of the plunger 12, the suction-exerting means is set in operation to create the exertion of suction through the tube 26 to thereby draw the string 7 down through the sleeve 20 as shown in Fig. 10. The result of this is that when the filled applicator, consisting of the tubes 22 and 23 with the tampon in the tube 22, is removed from the supports 14, 20, the string 7 will be found to be protruding from the end of the smaller tube 23 as shown in Fig. 11.

It will be clear from the foregoing, that the operation of inserting a tampon into an applicator may be speedily and accurately performed by the means described. In carrying out the operation, a tube 23 is dropped into the annular chamber 21 until it comes to rest upon the surfaces of the table 18 at the bottom of the chamber 20. The upper end portion of the tube 23 will then be found to be extending above the top of tube 14 to the height of the projecting part of the sleeve 20 shown in Fig. 8. Next a tube 22 is slipped over the projecting part of the tube 23, the tube 22 seating on the flange 16 which determines the extent to which it telescopes with the inner tube 23. When the two tubes 22 and 23 are placed as described, the compressing tube 11 then descends and the plunger 12 therein forces the tampon down into the tube 22 until the lower end of the tampon contacts with the upper end of sleeve 20 as well as with the upper end of the ejector tube 23. This contact of the tampon with the tube 23 and the sleeve 20 serves to limit the extent of insertion of the tampon within the tube 22 and such insertion is preferably made to

such an extent as to allow a relatively small portion of the end of the tampon to protrude above the top of the tube 23, as indicated at 27 in Fig. 11. Since the tendency of the compressed sponge material is to expand, this projecting part 27 of the sponge will spread or expand slightly thus forming a protecting soft and compressible head that flares over the upper edge 28 of the tube 23, this part shielding said edge and preventing it from harshly contacting with the walls of the vagina when inserted therein.

After the tampon has been inserted into the tube 22, the compressing tube 11 and its plunger member 12 ascends so that the two tubes 22 and 23, with the tampon contained within the tube 22, can be lifted as a unit to be packed in a suitable container, Cellophane-wrapped or otherwise suitably packaged.

While I have herein described the tampon as being of a certain wedge or "keystone" shape and having its withdrawal string attached in a particular manner, it will be obvious that these details of construction may be altered materially. For example, in Figs 12 and 13 the tampon is shown as being composed of a piece of sheet-like cellulose sponge material transversely folded or doubled upon itself on the line 32 to form a body of double thickness, the two thicknesses of the body being indicated respectively at 33 and 34. The withdrawal string 33 is looped about the body as shown in Fig. 13 and thereafter the compression and insertion of the tampon into an applicator may be had as described with respect to the tampon body of Fig. 2.

What I claim is:

1. In the method of making tampons, the step of centrally supporting a wedge or keystone-shaped, flat section of sponge-like material and guiding it into and rotating it within a compressing and forming tube to form it into a cylinder of substantially uniform diameter.

2. In the method of making tampons, the steps of centrally supporting a wedge or keystone-shaped, flat section of sheet material of absorbent nature, guiding it into and rotating it within a cylindrical compressing and forming tube and then forcing the tampon, then in compressed cylindrical form, out of the tube.

3. In the method of making tampons, the steps of supporting a wedge or keystone-shaped, flat section of absorbent sheet material, guiding it into and rotating it while forcing it into a cylindrical compressing tube and forcing it out of said tube and directly therefrom into a tubular applicator body.

4. In the method of making a tampon, the steps of cutting a flat, relatively thick section from a sheet of sponge-like material and twisting said section inside of a conical guide and therefrom into a cylindrical tube to form it into cylindrical shape and then projecting it out of said tube and directly into a cardboard applicator tube.

5. In the method of making a tampon, the steps of cutting a flat, relatively thick wedge-shaped tampon body from a sheet of compressible, absorbent material, applying a pull-string to the tampon body, guiding the tampon into and rotating the tampon within a cylindrical compressing-tube to thereby fold parts of the body and compress the body into cylindrical shape, and inserting the cylindrical body within a cardboard tube.

6. In the method of making tampons, the steps of forming a tampon into a flat, substantially wedge-shaped body, gripping said body and guiding the same into and rotating the same within a cylindrical former to thereby compress it into a cylinder of substantially uniform diameter, supporting a pair of tubes in an upstanding position with one of the tubes having a part projecting above the top of the other tube, and inserting the compressed tampon into the projecting part of said one tube.

7. In the method of making tampons, the steps of transversely severing a sheet of sponge material into a plurality of wedge-shaped sections, applying a withdrawal string to each of said sections, gripping each section and rotating the section, inserting the section into a guide and therefrom into a tubular passage while the section is being rotated to thereby compress the section and cause it to conform in shape to the interior of said passage, supporting an applicator tube and an inner push-tube in an upstanding position while said tubes are arranged telescopically and with a part of the applicator tube arising above the top of the push-tube, and forcing the compressed tampon section from the passage and into the applicator tube.

8. In a method of making tampons as provided for in claim 7 and including the step of suctionally drawing down the free end of the withdrawal string through the push-tube while the tampon is being inserted into the applicator tube.

JOSEPH R. CROCKFORD.
